UNITED STATES PATENT OFFICE.

JACOB H. STULL, OF FREMONT, OHIO.

RAIL-JOINT.

1,227,853.

Specification of Letters Patent. Patented May 29, 1917.

Application filed February 27, 1917. Serial No. 151,206.

To all whom it may concern:

Be it known that I, JACOB H. STULL, a citizen of the United States, residing at Fremont, in the county of Sandusky and State of Ohio, have invented certain new and useful Improvements in Rail-Joints; and I do declare the following to be a full, clear, and exact description of the invention, such as will enable others skilled in the art to which it appertains to make and use the same.

This invention relates to new and useful improvements in rail joints and the primary object of the invention is to provide a specially designed type of chair capable of easily and securely connecting the ends of the rail, and so connected as to enable certain parts of the chair to be easily removed for making repairs, or for any other purpose.

One object of the invention is to provide a new and improved construction of rail joint equipped with means capable of tightening the parts automatically when the rail joint is subjected to jarring and vibration whereby any loosening of the parts will be taken up.

Another object of this invention is to provide a device of this character which is simple and durable in construction, inexpensive to manufacture, and one which will be very efficient in operation.

With these and numerous other objects in view, my invention consists of the novel features of construction, combination and arrangement of parts which will be herein referred to and more particularly pointed out in the specification and claims.

In the accompanying drawings:

Figure 1 is a perspective view of the rail joint in use;

Fig. 2 is a vertical sectional view on line 2-2 of Fig. 1;

Fig. 3 is a detail perspective view of the locking wedge member;

Fig. 4 is a detail perspective view of a modified form of the bolt having a lock washer applied thereon and the ear being formed without teeth;

Figs. 5 and 6 are vertical sectional views showing modified forms of locking wedge members.

The rail joint comprises in its construction a rail chair constructed of cast metal, or other suitable material and having a horizontal bottom portion or base 1 and provided with laterally spaced upstanding

walls 2 and 3 adjacent its opposite sides. The projecting wall 2 extends inwardly and upwardly as shown at 4, and is so constructed that the same is adapted to form 60 an integral fish plate 5, adapted to be positioned against one side of the rails that are positioned within the chair.

The projecting wall 3 of the chair is formed integral therewith but does not extend inwardly, and this chair is provided with a separate fish plate 6, which is adapted to be positioned between the wall 3 and the adjacent side of the rails in the chair, in such relation that its outer side 7 is spaced 70 laterally from the inner side 8 of said wall. This inner side 8 of the wall is inclined longitudinally for a purpose to be herein-after more fully described. The separate fish plate 6 is of sufficient thickness so as 75 to form a substantial support for the sides of the rails and extends from the head to the flange of said rails, as clearly shown in Fig. 1 of the drawings. The outer wall 7 and the inclined inner wall 8 of the plate 80 and wall respectively, are grooved longitudinally as shown at 9 and 10, the groove 9 in the wall 7 being T-shaped in cross section, and the groove 10 in the inclined side of the wall 3 is formed with a substantially 85 enlarged portion as clearly shown in Figs. 1 and 2 of the drawings. The separate fish plate 6 is of a length corresponding to the length of the wall 3, and to securely hold these two parts in position, oppositely 90 spaced from each other, I provide the wall 3 with an upwardly projecting lug 11 on the top of the same, adjacent one end. Projecting laterally from the top of the fish plate 6 adjacent the outer side 7 of the same 95 is an integral arm 12, that extends across the space between the plate and wall 3, and is adapted when the plate is oppositely spaced from the wall to engage the stop lug 11, thereby locking the plate in position 100 and preventing the same from moving forwardly any further. The purpose of this lock including the stop lug 11 and arm 12 is to prevent longitudinal movement of the fish plate 6 while a locking member comprising a wedge block 13 is driven into position between the plate and stationary wall. 105

The wedge block 13 has one side flat and positioned against the other side of the fish plate 6, but the side of said wedge is inclined so that it co-operates with the inclined side 8 of the wall 3, to bring about 110

the required wedging action to securely lock the parts together. This wedge block 13 is slightly longer than the plate or wall 3 and when in position its rear end 14 will project therefrom as clearly shown in Fig. 1 of the drawings. The wedge block 13 has its opposite sides provided with projecting rib members 15 and 16 which are correspondingly shaped to the grooves in the plate and wall respectively, and which are adapted to engage the same when the wedge block is driven in position to prevent vertical movement of the block. This block is also held against vertical movement by the projecting arm 12 of the fish plate that extends across the top of the same.

To securely lock the wedge block 13 in position between the plate 6 and wall 3 of the chair, the projecting rear end 14 of said block is provided with a laterally extending apertured ear 17, that is disposed adjacent the end of the wall 3. The plate or wall 3 has a recess 18 in its upper face at a point near the end adjacent the apertured ear 17, thereby leaving at said end a portion 19 which is apertured, so that when the wedge block 13 is in position a headed locking bolt 20 is adapted to be positioned through the apertures in these parts and to be secured therein to securely lock the block to the wall and prevent the block from being retracted or released.

The bolt 20 has mounted on its free end that is disposed within the recess 18 a locking nut 21, and positioned between the nut 21 and the portion 19 on the wall and surrounding the bolt is a coiled spring 22. The lower surface of the headed portion of the bolt 20 is provided with a plurality of teeth 23 thereon to engage the teeth 23' on the outer wall of the ear 17, or positioned between the same and the outer surface of the ear 17 as shown in a modified form I may use a spring locking washer 24, that has one end adapted for engagement with the teeth and the other positioned in a recess 25 in said ear. Either of these means will securely lock the bolt in position and will prevent the same from rotating. The coiled spring 22 will exert a constant tension on the bolt, and consequently will tend to throw the block 13 further into position, thereby compensating for the loosening of the parts due to the jarring vibration to which the chair is subjected. This will automatically tighten up the loose parts by driving the wedge block 13 further into position and will prevent the separate parts of the chair from working loose.

The base 1 of the chair is provided adjacent the opposite ends of the rails disposed therein with openings 26 therethrough that are adapted to allow fastening members 27 to be driven therethrough, and hence into the tie on which the chair is positioned.

These members are driven through the base to the chair before the separate fish plate 6 and wedge block are placed in locked relation, and to allow the separate fish plate 6 to easily slide in position over the projecting head portions, each of these fastening means is provided with a longitudinally extending groove 28 which allows said plate to easily slide over the heads, which will be positioned within this groove. The chair is additionally held in position by fastening members which are driven through the notched portions 29 on the opposite sides of the chair.

In Figs. 5 and 6 of the drawing I have shown end views of the chair in locked position illustrating additional types of locking means between the opposite sides of the wedge block and the outer side of the fish plate and inner side of the stationary upright wall 3. In Fig. 5 of the drawing the wedge block is provided with substantially concaved opposite sides 30, and into these sides are adapted to fit the projecting convexed outer side 31 of the fish plate 6, and inner side 31' of the wall 3. Fig. 6 shows a slightly different type whereby the fish plate 6 is provided with a rib 32 having flat sides, and adapted to be positioned in a correspondingly shaped groove 33 in the adjacent side of the wedge block while the other side of said block has a spaced triangular shaped in cross section rib 34 adapted to be positioned in a correspondingly shaped groove 35 in the inner side of the wall 3 of the chair. The employment of any of these types of interlocking fastening means will prevent vertical movement of the wedge block 13 when in operative position.

The parts of the device may be easily assembled by positioning the chair on the tie, and placing the opposite ends of the rails therein, with one side of the same against the integral fish plate 5 which is formed with the chair. When in this position the separate fish plate 6 on the opposite side of the rail is then moved into position, the interlocking stop members 11 and 12 limiting the movement and owing to the width of this plate, a space will be left between its outer side and the projecting wall 3 at this side of the chair. The wedge block 13 is then positioned in this space and by the herein described various locking means, this block will be held against vertical movement and the separate plate will be also held stationary when the block is being driven between the same and the wall 3. When the wedge block is in position, the bolt 20 connects the rear end of the block with the wall 3 in the manner hereinbefore fully described, thereby securely locking the block in position between the plate and wall and preventing the same from being retracted. The spring tension used in the connecting

bolt automatically tightens the block in position when the parts become worn due to the constant jarring and vibration to which these types of devices are subjected. The 5 block 13 will always be tightly wedged between the separate plate and the stationary wall, and the joint will be tightly locked. Upon releasing the connecting bolt 20 the parts of the device may be easily detached 10 and the rails quickly removed.

From the foregoing description of the construction and operation of my improved rail joint the manner of applying the same to use, and the operation thereof, will be 15 readily understood, and it will be seen that I have provided a simple and efficient device of this character for carrying out the objects of the invention.

I claim:

20 1. A railway chair comprising a base having laterally spaced upstanding walls formed in one piece therewith, one of said walls extending inwardly to form a fish plate, the other wall being longitudinally inclined with 25 respect to the first named wall, a separate fish plate adapted to be positioned in spaced relation with respect to the inclined wall for engaging the track rail, a wedge block adapted to be positioned between said fish plate 30 and the inclined wall, interengaging locking means on the sides of said block to prevent vertical movement of the block, a removable fastening member adjustably connecting one end of said block and the inclined wall, and 35 coöperating locking means to hold the separate fish plate stationary in spaced relation with the inclined wall when the wedge block is being driven in position.

2. A railway chair comprising a base having laterally spaced upstanding walls formed 40 in one piece therewith, one of said walls extending inwardly to form a fish plate, the other wall being longitudinally inclined with respect to the first named wall, a separate fish plate adapted to be positioned in spaced 45 relation with respect to the inclined wall for engaging the track rail, said plate being of a corresponding length therewith, a wedge block adapted to be positioned between said 50 fish plate and the inclined wall, interengaging locking means on the sides of said block to prevent vertical movement of the block, a removable fastening member adjustably connecting one end of said block and the inclined 55 wall, and stop members carried by said separate locking plate and wall adapted for coöperative engagement to hold the plate stationary when the wedge block is being driven in position.

60 3. A railway chair comprising a base hav-

ing laterally spaced upstanding walls formed in one piece therewith, one of said walls extending inwardly to form a fish plate, the other wall being longitudinally inclined with respect to the first named wall, 65 a separate fish plate adapted to be positioned in spaced relation with respect to the inclined wall for engaging the track rail, said plate being of a corresponding length therewith, a wedge block adapted to be positioned between said fish plate and the inclined wall, interengaging locking means on the sides of said block to prevent vertical movement of the block, a removable fastening member adjustably connecting one end of said block 70 and the inclined wall, an upwardly projecting lug on the top of the inclined wall and a laterally projecting arm on the top of said separate fish plate adapted to engage the lug when the plate is oppositely disposed from said wall whereby the plate will be held stationary when the wedge block is driven in position.

4. A railway chair comprising a base having laterally spaced upstanding walls formed in one piece therewith, one of said walls extending inwardly to form a fish plate, the other wall being longitudinally inclined with respect to the first named wall, a separate fish plate adapted to be positioned in spaced relation with respect to the inclined wall for engaging the track rail, a wedge block adapted to be positioned between said fish plate and the inclined wall, interengaging locking means to hold the separate fish plate in spaced relation with the wall when the wedge block is being placed in position, locking means on the sides of said block adjacent the wall and plate to prevent vertical movement of the block, a laterally projecting 100 apertured ear on one end of said block or ear, said ear having teeth on its outer wall, a portion on the adjacent end of the inclined wall having an aperture therethrough aligning with the aperture in the ear of the block, a headed bolt positioned through said apertures, the head of said bolt having teeth on its inner face, a spring locking washer between the head of the bolt and the ear on the block, a nut on the other end of said 105 bolt, and a coiled spring on the bolt between the nut and the projecting portion of the inclined wall.

In testimony whereof I have hereunto set my hand in the presence of two subscribing 110 witnesses.

JACOB H. STULL.
